PAVEMENT JOINT

Alan E. Brickman and George A. Gleason,
Worcester, Mass., assignors to The American
Steel and Wire Company of New Jersey, a cor-
poration of New Jersey

Application January 15, 1938, Serial No. 185,211

6 Claims. (Cl. 94—18)

This invention relates to joints, and more particularly to those which are used in concrete pavement construction to compensate for expansion and contraction due to changes in temperature and moisture content.

Joints of the type described are subjected to several deleterious factors and consequently give rise to considerable difficulty. Pre-molded felt or paper joints which are saturated with asphalt 10 extrude from the pavement as the concrete sections expand, and present a bumpy surface to traffic. After the pavement contracts, spaces are left on either side of the pre-molded fillers which permit the entrance of dirt and water. If water 15 enters the joint it might later freeze and damage the pavement, while dirt becomes packed with the result that the pavement is not permitted adequate space for expansion and therefore "heaves" or "buckles".

It is among the objects of the present invention to provide an efficient and inexpensive expansion and contraction joint for concrete pavement which will also function to transfer the load from one section of concrete to the other.

The foregoing and other objects will be apparent after referring to the drawings, in which:

Figure 1 is a fragmentary side elevation of the device of the invention;

Figure 2 is a sectional view on the line II—II of Figure 1;

Figure 3 is a view similar to Figure 2 but disclosing the device after it has been completely installed; and

Figure 4 is a view similar to Figure 3 but disclosing the device after it has been completely installed and while under contraction as the result of the expansion of the pavement.

Referring more particularly to the drawings, the numeral 2 designates an elongated U-shaped 40 sheet metal member, the vertical portions of which are greatly elongated and substantially parallel to each other. The upper ends of the vertical portions of the U-shaped member 2 are bent convergently, as shown at 3, and then into 45 parallelly opposite reverse curves 4 whose extremities are in spaced relationship. The parallelly opposite reverse curves 4 of the U-shaped member 2 are connected by an enclosing molded rubber seal 5 which is shaped to conform to the 50 entireties of the deformations thereof and close their extremities. The lower ends of the vertical portions of the U-shaped member 2 are connected by an integral curved portion 1.

The U-shaped member 2 is disposed within 55 and welded to a U-shaped suspension strap 9

which functions in a manner to be later described. The U-shaped suspension strap 9 embodies vertical portions which are elongated and substantially parallel to each other and right-angularly extending horizontal portions 10. The horizontal portions 10 of the U-shaped suspension strap 9 are provided with press-indent portions 12 which extend upwardly therefrom to provide a good bond in the concrete blocks. The lower ends of the vertical portions of the U-shaped suspension strap 9 are connected by an integral curved portion 13.

The exterior of the integral curved portion 1 of the U-shaped member 2 is spaced from the interior of the integral curved portion 13 of the U-shaped suspension strap 9 by means of a spacer block 14 which is constructed and arranged to dispose the upper ends of the vertical portions of the U-shaped member 2 above the horizontal portions 10 of the U-shaped suspension strap 9.

Immediately below the U-shaped member 2 there is disposed a horizontally extending bearing plate 15 having a central aperture 16 of sufficient size to permit the projection of the lower end of the U-shaped suspension strap 9 therethrough. 25 The aperture 16 in the horizontally extending bearing plate 15 lies over a recess in the ground which provides a seat for the integral curved portion 13 of the U-shaped suspension strap 9. The horizontally extending bearing plate 15 carries 30 downwardly depending plates 17 at the sides of the aperture 16 for lending support to the U-shaped suspension strap 9.

The ends of the horizontally extending bearing plate 15 are slidably supported in sleeves 18 which 35 rest upon the ground. The recess in the ground which provides a seat for the integral curved portion 13 of the U-shaped suspension strap 9 is undercut outwardly to the sleeves 18, thereby enabling the latter to act as the only supports for 40 the horizontally extending bearing plate 15.

Sheet-metal shields 20 are provided to extend along and around the vertical portions of the U-shaped suspension strap 9. These shields 20 are positioned to provide voids between themselves 45 and the U-shaped suspension strap 9, thereby permitting the movement of the latter with the concrete slabs. The sleeves 18 on the ends of the horizontally extending bearing plate 15 are similarly positioned. Thus, there is eliminated the 50 danger of concrete burrs which might obstruct the smooth movement of the concrete slabs on the horizontally extending bearing plate 15.

The U-shaped suspension strap 9 is welded to the horizontally extending bearing plate 15 in or- 55

der to enable correct installation and eliminate the danger of the creeping of the former when in tension.

Referring to Figure 1, of the drawings, there is illustrated a tapered extension 22 for the U-shaped member 2. This tapered extension 22 is for use on thickened edge pavement and extends the U-shaped member 2 to the sub-grade.

Referring again to Figure 1, the ends of the U-shaped member 2, and also the tapered extensions 22 if such are used, are sealed by vertical molded rubber strips 24 thereby excluding water etc., and assisting installation by accommodating slight span variations. The strips 24 are held against the ends of the U-shaped members 2 and tapered extensions 22 by means of forms 25.

The molded rubber seal 5 and U-shaped member 2 are held in position by vertical posts 27 carrying horizontally extending supporting lugs 28 at the time of pouring the concrete.

While we have shown and described one specific embodiment of the present invention, it will be seen that we do not wish to be limited exactly thereto, since various modifications may be made without departing from the scope of the invention as defined by the following claims.

We claim:

1. A joint for concrete pavement and the like comprising a pair of side-walls adapted to substantially abut the ends of the adjacent concrete sections, said side-walls being closed at their upper and lower ends, a bearing plate beneath the ends of the adjacent concrete sections, said bearing plate being constructed and arranged to support the ends of said adjacent concrete sections, and a U-shaped member for maintaining the ends of the adjacent concrete sections in alignment, the open ends of said U-shaped member being provided with lateral extensions which are embedded in the adjacent concrete sections, said bearing plate having an aperture to receive said U-shaped member.

2. A joint for concrete pavement and the like comprising a pair of side-walls adapted to substantially abut the ends of the adjacent concrete sections, said side-walls being closed at their upper and lower ends, a bearing plate beneath the ends of the adjacent concrete sections, said bearing plate being constructed and arranged to support the ends of said adjacent concrete sections, and a U-shaped member for maintaining the ends of the adjacent concrete sections in alignment, said U-shaped member being disposed to embrace the lower ends of said side-walls and extending through an aperture in said bearing plate, the open ends of said U-shaped member being provided with lateral extensions which are embedded in the adjacent concrete sections.

3. A joint for concrete pavement and the like comprising a pair of side-walls adapted to substantially abut the ends of the adjacent concrete sections, said side-walls being closed at their upper and lower ends, a bearing plate beneath

the ends of the adjacent concrete sections, said bearing plate being constructed and arranged to support the ends of said adjacent concrete sections, a U-shaped member for maintaining the ends of the adjacent concrete sections in alignment, said U-shaped member being disposed to embrace the lower ends of said side-walls and extending through an aperture in said bearing plate, the open ends of said U-shaped member being provided with lateral extensions which are embedded in the adjacent concrete sections, and bearing means for permitting the sliding movement of said bearing plate.

4. A joint for concrete pavement and the like comprising a pair of side-walls adapted to substantially abut the ends of the adjacent concrete sections, said side-walls being closed at their upper and lower ends, a bearing plate beneath the ends of the adjacent concrete sections, said bearing plate being constructed and arranged to support the ends of said adjacent concrete sections, a U-shaped member for maintaining the ends of the adjacent concrete sections in alignment, said U-shaped member being disposed to embrace the lower ends of said side-walls and extending through an aperture in said bearing plate, and means for spacing the lower ends of said side-walls from the bottom of said U-shaped member, the open ends of said U-shaped member being provided with lateral extensions which are embedded in the adjacent concrete sections.

5. In a transload highway joint comprising a pair of oppositely facing slab sections, a unitary base element underlying the joint and extending in opposite directions for a substantial distance beneath each slab, and a pair of upright members carried by said unitary base element so as to extend upwardly in substantial parallelism between the slab sections, respectively adjacent each of the end faces of the latter, the upper extremity of each upright member being turned to penetrate into its respectively proximate slab section in a substantially horizontal direction.

6. In a transload highway joint comprising a pair of oppositely facing slab sections, a unitary base element underlying the joint and extending in opposite directions for a substantial distance beneath each slab, and a pair of upright members carried by said unitary base element so as to extend upwardly in substantial parallelism between the slab sections, respectively adjacent each of the end faces of the latter, the upper extremity of each upright member being turned to penetrate into its respectively proximate slab section in a substantially horizontal direction, said upright members being so secured to said unitary base element as to be afforded relative movement toward and away from each other incident to the movement of the slabs when expanding and contracting.

ALAN E. BRICKMAN.
GEORGE A. GLEASON.
